UNITED STATES PATENT OFFICE

146,113

DESIGN FOR A LAMP

Dale J. McGinnis, Chicago, Ill.

Application November 28, 1945, Serial No. 124,143

Term of patent 3½ years

(Cl. D48—20)

To all whom it may concern:

Be it known that I, Dale J. McGinnis, a citizen of the United States of America, residing at Chicago, in the county of Cook and State of Illinois, have invented a new, original, and ornamental Design for a Lamp, of which the following is a specification, reference being had to the accompanying drawings, forming a part thereof.

In the drawings:

I claim:

The ornamental design for a lamp, as shown.

DALE J. McGINNIS.
